(57) **CLAIM**

We claim the ornamental design for a die cutting machine with stripping and blanking, as shown and described.

DESCRIPTION

FIG. 1 is a perspective view of the front, top, and right side of a die cutting machine with stripping and blanking;
FIG. 2 is a perspective view of the front, top, and left side of a die cutting machine with stripping and blanking;
FIG. 3 is a perspective view of the back, top, and right side of a die cutting machine with stripping and blanking;
FIG. 4 is a front view thereof;
FIG. 5 is a back view thereof;
FIG. 6 is a right view thereof;
FIG. 7 is a left view thereof;
FIG. 8 is a top view thereof; and,
FIG. 9 is a bottom view thereof.
